KVAELSTOFAKTIESELSKAB, OF CHRISTIANIA, NORWAY.

METHOD OF PRODUCING ROTATING ELECTRIC ARCS.

1,175,252.

Specification of Letters Patent. Patented Mar. 14, 1916.

Application filed September 15, 1913. Serial No. 789,857.

To all whom it may concern:

Be it known that I, ANTONIUS Foss, a subject of the King of Norway, residing at Christiania, Norway, have invented certain new and useful Improvements in Methods of Producing Rotating Electric Arcs; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention has for its object a method of producing rotating electric arcs.

When an electric arc is subjected to the action of a revolving gas current, which at the same time draws the arc out in the direction of the axis of the rotation then the arc will tend to place itself in the center of the gas whirl the well known long stable arcs being hereby obtained. Even if the arc is established between two electrodes 25 which are for instance of an annular form or between a rod shaped electrode and an annular electrode the whirling gas will have the effect that only quite a small part of the arc will move on the surface of a body of 30 revolution, the base of which is constituted by the electrodes or the electrode respectively while the greater part will be situated in the center of the gas whirl. If it were possible to cause the whole arc to move on the surface 35 of a body of rotation instead of being substantially in the form of a rod, then it would no doubt be possible to obtain important advantages as to the output of nitrous products. Further the length of the furnace for a certain amount of energy would 40 be reduced in proportion as the surface of the arc increases and also other advantages will result. According to the present invention arcs of this character are obtained when 45 proceeding in the manner hereinafter described with reference to the accompanying drawing, in which—

Figure 1 illustrates diagrammatically one embodiment of the invention. Fig. 2 illustrates another embodiment of the invention. Fig. 3 is a section taken through the tangential gas passages B.

In the example illustrated in Fig. 1 the operation is as follows: A is the furnace, 55 which may be made of any suitable mate-

rial and the sectional area of which is dependent upon the shape of the electrodes. In this furnace the electrodes E—E' are placed, which in this special example have an annular form. At one of the electrodes 60 gas is blown into the furnace at the periphery of the same through tangential channels B. Of course the gas may also be introduced through holes which are evenly distributed over the whole surface of the furnace. Inside of or concentric with the electrode E is placed a pipe B' which according to the size of the electrodes, blows the gas into the furnace as a jet annular in section. The gas jet may of course be of any other 70 sectional form. When an arc is now established between the electrodes E, E' for instance by short circuiting the electrodes in a suitable manner, and gas is at the same time blown in through the peripherally arranged channels B which are placed more or less at an angle to the axis of the furnace, then an arc will be formed, which tends to place itself in the center of the gas whirls. However, if at the same time gas is blown 75 in through the pipe B' inside of the annular electrode then the arc will be blown outwardly and on rotating it will move along the surface of a body of rotation whose form depends upon the form of the electrodes and the power of the gas current. The gas leaves the furnace at the electrode E, where suitable cooling means may be arranged.

Another embodiment of the invention is 80 illustrated in Fig. 2, where two furnaces are combined into one in such manner, that the electrodes E, E' are situated one in each end of the furnace. Inside of the electrodes E, E' the supply pipes B'—B' are arranged. 85 In the periphery of the furnace near to the annular electrodes the obliquely situated gas supply channels B—B are arranged. As mentioned these channels may also be arranged over the whole surface of the furnace. The gas is drawn off at suitable 90 points of the circumference of the furnace for instance at C or also in the center of the same and by means of cooled pipes suitably arranged. In whatever manner the gases are 95 discharged, a part of the same must pass through the arc, whereby an energetic heating of the gas is effected. As will be understood from the above one may in this manner by the simplest possible means produce 100 105 110

arcs having a very great surface and consuming large amounts of electrical power. It is evident that arcs of this kind are more profitable for effecting chemical reactions in gases than the long rod shaped arcs hitherto employed, the gas coming according to the present method in a much more intimate contact with the arc on account of the permanent tendency of the arc to place itself in the center of the gas whirl, which is prevented by the current of air, which is blown in inside of the electrode and within the arc annulus. As a consequence hereof the efficiency will be increased correspondingly. Furthermore a furnace constructed in accordance with this invention can be made considerably shorter than such in which rod shaped arcs are produced, and this again involves a reduction in the cost of the plant and also other advantages.

I claim:

1. The method of forming rotating arcs, which comprises striking the arc between suitable electrodes and supporting the arc throughout its length between two substantially concentric currents of gas.

2. The method of forming rotating arcs, which comprises striking the arc between suitable electrodes and supporting the arc throughout its length between two substantially concentric annular currents of gas.

3. The method of forming rotating arcs, which comprises striking an arc between two opposite electrodes, and supporting the arc throughout its length between two currents of gas acting in opposite directions.

4. The method of forming rotating arcs, which comprises striking the arc between suitable electrodes and supporting the arc throughout its length between a rotating gas current and a concentric longitudinal gas current.

5. The method of forming rotating arcs, which comprises striking an arc capable of rotation between suitable electrodes, directing a plurality of gas jets substantially to the exterior of the arc and producing a gas current within the arc substantially along its center, between said electrodes.

6. The method of forming rotating arcs, which comprises striking an arc capable of rotation between suitable electrodes, and supporting the arc between oppositely directed internal gas currents and oppositely directed external gas currents.

7. The method of forming rotating arcs, which comprises striking an arc capable of rotation between suitable electrodes, and supporting the arc between oppositely directed internal gas currents and oppositely directed external gas currents, said internal

and external gas currents exerting substantially opposite radial pressures.

8. The method of forming rotating arcs, which comprises striking an arc capable of rotation between suitable electrodes, subjecting the arc exteriorly to the action of rotating currents of gas from opposite directions and interiorly to oppositely directed currents of gas.

9. The method of forming rotating arcs, which comprises striking an arc capable of rotation between suitable electrodes, supplying to the exterior of the arc from its opposite ends a number of substantially tangentially directed gas jets and to its interior oppositely directed gas jets.

10. The method of forming rotating electric arcs, which comprises establishing a long arc capable of performing a rotating motion around the axis of the furnace, introducing gas inside of the surface of rotation formed by the said rotating arc substantially in the direction of the axis of rotation and also introducing gas outside of the surface described by the rotating arc.

11. In an electric furnace producing a rotating arc, a furnace chamber, spaced electrodes therein, a gas supply chamber adjacent one electrode having jet orifices, and a gas supply pipe at said electrode arranged to supply gas through the middle thereof and to form a substantially gaseous surface of revolution for supporting the arc throughout its length.

12. In an electric furnace producing a rotating arc, a furnace chamber, annular electrodes at opposite ends thereof, a gas supply chamber surrounding one of the electrodes and having jet orifices directed substantially tangential to said electrode, and an annular gas supply pipe concentric with said electrode, arranged to form a supporting core for said arc.

13. In an electric furnace producing a rotating arc, a furnace chamber, an annular electrode at each end thereof, a gas supply chamber at each end having jet orifices leading to the furnace chamber, annular gas supply pipes substantially concentric with the electrodes arranged to direct opposed annular gas jets through the annular electrodes, and means in the furnace wall between the electrodes to take off the reaction products.

In testimony that I claim the foregoing as my invention, I have signed my name in presence of two subscribing witnesses.

ANTONIUS FOSS.
